(57) **CLAIM**

The ornamental design for glasses, as shown and described.

DESCRIPTION

FIG. 1 is a front elevational view of glasses showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of the encircled portion '9' in FIG. 1;

FIG. 10 is an enlarged view of the encircled portion '10' in FIG. 5; and,

FIG. 11 is an enlarged view of the encircled portion '11' in FIG. 6.

The broken lines shown in the drawings are for the purpose of illustrating portions of the article that form no part of the claimed design.

The long-dash short-dash broken lines in FIGS. 1, 5, 6, and 9-11 depict the limits of the enlarged views and form no part of the claimed design.

1 Claim, 11 Drawing Sheets
